DESIGN FOR A COAT

Joseph Matis, New York, N. Y.

Application June 3, 1938, Serial No. 77,541

Term of patent 3½ years

To all whom it may concern:

Be it known that I, Joseph Matis, a citizen of the United States of America, residing in city of New York, county of New York, and State of New York, have invented a new, original, and ornamental Design for a Coat, of which the following is a specification, reference being had to the accompanying drawing, forming part thereof, wherein

Fig. 1 is a front view of a coat showing my new design.

Fig. 2 is a rear view thereof.

The characteristic feature of my design resides in the specific sleeves and in the specific vestee in combination with the coat as shown.

I claim:

The ornamental design for a coat, substantially as shown and described.

JOSEPH MATIS.
